UNITED STATES PATENT OFFICE.

LEVI BEAULIEN, OF WOONSOCKET, RHODE ISLAND.

IMPROVEMENT IN WASHING-MACHINES.

Specification forming part of Letters Patent No. **139,107**, dated May 20, 1873; application filed April 29, 1873.

To all whom it may concern:

Be it known that I, LEVI BEAULIEN, of Woonsocket, in the county of Providence and State of Rhode Island, have invented a new and valuable Improvement in Washing-Machines; and I do hereby declare that the following is a full, clear, and exact description of the construction and operation of the same, reference being had to the annexed drawing making a part of this specification, and to the letters and figures of reference marked thereon.

Figure 1 of the drawing is a representation of a top view of my invention. Fig. 2 is a sectional view of the same.

This invention has relation to washing-machines; and it consists in the construction and novel arrangement, in a semi-cylindrical or curved-bottom tub, of the different semi-cylindrical washers or rubbers, independently pivoted to the walls of the tub and to arms projecting into the tub, and operated by levers connected by pitmen with cranks of the operating-shaft, having such angular relation to each other that the movements of the washers will be made in different times, or successively, thereby avoiding the crowding of the goods at one end of the tub.

In the accompanying drawing, the letter A indicates the tub of the washing-machine, provided with suitable standards B and the side arms C. This tub is, preferably, semi-cylindrical in form, and has a double wall formed by securing the sheet of zinc a to the edges of the side pieces D and to the outside of the boards E, and a sheet of corrugated or fluted zinc, F, to the inside of said boards E. From the end to which the arms C are secured the boards G project into the tub and partly across the same, and are slotted vertically, as at b, to serve as journal-seats for the journals of the rubbers. To the upper edges of one or more of these arms, and to one or both walls of the tub, are

pivoted the bridges c. In the drawing two of the arms or boards G are illustrated, forming, with the side walls of the tub, bearings for the journals of three independent washers, H. Each of these washers consists of two semicircular cheeks, d, connected by a number of rounded slats or bars, e, and a center board, g, through which passes the upright bar h, which is stepped in the central rubbing-bar e' at one end, and at the other or upper end is pivoted to the pitman k, by which it is connected with its independent crank l of the crank-shaft z. The crank-shaft is journaled in suitable seats in the arms C, and its cranks are arranged in angular relation to each other, so that the rubbers or washers H will be moved back and forth in different times in the tub, thereby avoiding the banking or packing of the goods being washed in one place.

When it is desired to remove the goods from the tub the washers are raised and the bridges c are thrown transversely underneath to support the washers above the goods and out of the tub.

Metallic bands n are used to bind the lower zinc bottom a firmly to the end boards E of the frame.

What I claim as my invention, and desire to secure by Letters Patent, is—

The combination, with a tub having the inner arms C parallel with its side walls, of the independently journaled washers H, levers h, pitman k, and crank-shaft z, having several cranks, l, one for each washer, arranged in angular relation to each other, substantially as specified.

In testimony that I claim the above I have hereunto subscribed my name in the presence of two witnesses.

Witnesses: LEVI BEAULIEN.

EDWARD BEAULIEN,
GEORGE A. WILBUR.
